UNITED STATES PATENT OFFICE

CARL WEEKS, OF DES MOINES, IOWA

POWDER HOLDER

Application filed May 7, 1929. Serial No. 361,196.

The object of my invention is to provide a very simple and inexpensive type of powder holder intended primarily for use by men.

More particularly, it is my purpose to provide a powder holder of the type having a lower casing member, an interior top powder retainer removably received and frictionally held therein, provided with a bent neck and adjustable closure therefore, and a movable top or covering forming a part of the casing.

With these and other objects in view, my invention consists in the construction, arrangement and combination of the various parts of my powder holder, whereby the objects contemplated are attained, as herein-after more fully set forth, pointed out in my claims, and illustrated in the accompanying drawings, in which:

20 Figure 1 shows a perspective view of a powder holder embodying my invention.

Figure 2 is a longitudinal, vertical, sectional view through the same.

Figure 3 is a similar view of a slightly modified form.

Figure 4 is a detail, sectional view taken on the line 4-4 of Figure 2.

Figure 5 is a top or plan view of another slightly modified form of powder holder.

30 Figure 6 is a transverse, vertical, sectional view of the holder shown in Figure 5; and

Figure 7 is a perspective view of a portion of an oval powder holder, illustrating a hinge connection therefor.

35 Heretofore in general practice, it has been the custom to make powder cans with a contracted neck and with no closure except one fitting snugly over the neck. These are of ordinary well known construction.

40 It is my purpose to make a powder holder adapted for containing face powder and the like of a peculiar type herein explained, which can be conveniently carried in a travelling bag or toilet kit, and which is of novel structure peculiarly adapted for its purposes.

In the accompanying drawings, I have shown in Figures 1, 2 and 4 a powder holder comprising a lower casing member indicated by the numeral 10 of concavo-convex form, 50 having an upstanding peripheral wall 12,

terminating in an outwardly projecting rolled flange 14.

This casing member is designed to hold powder which is covered in the first place by an interior top and in the second place by a second or top casing member, which will be later described.

The interior top comprises a portion 16 having a peripheral down-turned wall 18 to fit snugly and frictionally within the wall 12, in such manner that the portion 16 stands substantially above the level of the upper edge of the wall 12 as shown in the drawings.

The entire device is preferably longer than it is wide and may be oval as shown for instance in Figures 1, 2 and 7.

Near one end of the interior top, the member 16 is provided with an opening 20 from which extends an upstanding delivery neck 22, which has at its top an adjustable closure device 24.

The member 16 is so resilient that it may be pressed downwardly slightly with the finger for compressing the air above the powder 26 and forcing loose powder out through the neck 22. When pressure is released from the member 16, air is drawn into the holder thru the neck 22 and thereby loosens the powder so as to facilitate the discharge thereof upon subsequent pressure being applied to the member 16.

If desired the whole device comprising the bottom member and the interior top can be inverted for sprinkling powder.

My powder holder has a top or cover casing member comprising the portion 28 of concavo convex form provided with the downwardly extending peripheral wall 30 terminating in the outwardly extending flange 32. The wall 30 is designed to fit the portion of the wall 18 of the interior top that projects above the bottom casing member. The top or cover casing member is so arranged as to enclose and cover and protect the discharge neck 22 as shown in Figures 2 and 4.

There is a space as indicated for instance at A in Figure 2, which may contain a powder puff or other toilet accessory.

In Figure 3, I have shown a slightly modi-

fied form of my device in which the bottom casing member is the same as that already described.

The interior top comprises a member 34 similar to the member 16 and having a similar neck 22 and a downturned wall 36 similar to the wall 18. The member 34 differs from the member 16 in that the member 34 has a depressed or indented flat portion 38 in which the powder puff 40 may rest.

The form of device shown in Figure 3 has a top casing member similar to that already described.

In Figures 5 and 6, I have shown a slightly different form of my device, which is substantially rectangular in outline and has rounded corners. In the form of the device shown in Figures 5 and 6 is illustrated a bottom casing member having the concavo convex portion 42 with the upstanding peripheral wall 44 terminating in the outwardly projecting flange 46. The interior top is similar to those already described having the member 48 with the down-hanging peripheral wall 50.

In the form of device shown in Figures 5 and 6, however, the neck 22 similar to that already described is connected with a depressed portion 52 of the member 48, which would make it possible to build a somewhat thinner structure.

The top casing member of this form of the device has the concavo-convex portion 54 with the downwardly extending peripheral wall 56, having the outwardly inclined flange 58 hinged as at 60 to the flange 46.

I have in the present device provided a very simple and inexpensive cosmetic holder convenient to be carried in a traveling case or the like.

My device has its parts so arranged and constructed as to make it easy and convenient to recharge it with loose powder 26. This can be done by removing the interior top, inverting it, filling it with powder and then inverting the bottom casing member and slipping it over the wall of the interior top until the walls of said members are frictionally engaged for thus holding them together.

The discharge vent or opening in the complete container thus formed may be entirely covered and protected by the top casing member.

Where it is desirable to hinge the two parts 10 and 28 of an oval holder together, portions 62 and 64 may be formed as shown in Figure 7 for forming a straight wall for the hinge 60.

I claim as my invention:

1. In a powder holder, a bottom member having an upstanding peripheral wall terminating in a peripheral, outstanding flange, an interior top having a peripheral downwardly extending wall frictionally engaged within said first wall and projecting upwardly therefrom, said interior top having a discharge

opening and a neck extending upwardly therefrom provided with an adjustable closure means, and a top casing member having a downwardly inclined peripheral wall also terminating in a peripheral, outstanding flange for frictionally engaging around the wall of said interior top.

2. In a powder holder, a bottom member having an upstanding peripheral wall, an interior top having a peripheral downwardly extending wall frictionally engaged within said first wall and projecting upwardly therefrom, said interior top having a discharge opening and a neck extending upwardly therefrom provided with a transversely slidably adjustable closure means, and a top casing member having a concavo convex member and a downwardly inclined peripheral wall for frictionally engaging around the wall of said interior top, the portion of said interior top carrying the neck being down-set immediately adjacent the neck only substantially as shown.

3. In a powder holder, a bottom member having an upstanding peripheral wall, an interior top having a peripheral downwardly extending wall frictionally engaged within said first wall and projecting upwardly therefrom, said interior top having a discharge opening and a neck extending upwardly therefrom provided with an adjustable closure means, and a top casing member having a concavo convex member and a downwardly inclined peripheral wall for frictionally engaging around the wall of said interior top, said interior top being entirely flat and bendable for discharging powder from the holder and loosening it by a pumping action.

4. In a holder, an elongated bottom member having an upstanding peripheral wall, an elongated interior top having a peripheral downwardly extending wall frictionally engaged within said first wall and projecting upwardly therefrom, said interior top having a discharge opening and a neck extending upwardly therefrom provided with a horizontally slidably adjustable closure means, said neck being located relatively closer to one end of said interior top than the other and an elongated top casing member having a concavo convex member and a downwardly inclined peripheral wall for frictionally engaging around the wall of said interior top, said top and bottom casing members having a hinged connection.

Des Moines, Iowa, February 28, 1929.
